Primary Examiner—Holly Baynham
Attorney, Agent, or Firm—L.F. Hilbers

[57] CLAIM

The ornamental design for a shrub guard unit, as shown.

DESCRIPTION

FIG. 1 is a frontal perspective view of a first preferred embodiment of a shrub guard unit;

FIG. 2 is a front view of the shrub guard unit of FIG. 1;

FIG. 3 is a side view of the shrub guard unit of FIG. 1;

FIG. 4 is a rear view of the shrub guard unit of FIG. 1;

FIG. 5 is a top plan view of the shrub guard unit of FIG. 1; and,

FIG. 6 is a bottom view of the shrub guard unit of FIG. 1. The spike is slightly detached from the shrub guard unit in FIGS. 1-2 and 3-4 for clarity of illustration.
